(57) **CLAIM**

I claim the ornamental design for a rain gutter cover, as shown and described.

DESCRIPTION

FIG. 1 is a perspective view of the rain gutter cover of this invention;

FIG. 2 is a front view of the rain gutter cover of this invention;

FIG. 3 is rear view of the rain gutter cover of this invention;

FIG. 4 is a left hand view of the rain gutter cover of this invention;

FIG. 5 is a right hand view of the rain gutter cover of this invention;

FIG. 6 is a top view of the rain gutter cover of this invention; and,

FIG. 7 is bottom view of the rain gutter cover of this invention. The rain gutter cover is shown with a symbolic break in its length. The appearance of any portion of the gutter between the break lines forms no part of the claimed design.

1 Claim, 4 Drawing Sheets
